BOX FOR A WATCH

Jack Fairchild Fleming, Summit, N.J., assignor to The Bulova Watch Company, Flushing, N.Y., a corporation of New York

Application April 9, 1959, Serial No. 55,424

Term of patent 7 years

(Cl. D58—12)

FIG. 1.

FIG. 2.

FIG. 3.

FIG. 4.

Fig. 1 is a perspective view of a box for a watch showing my new design.

Fig. 2 is a top plan view thereof.

Fig. 3 is a side elevational view thereof.

Fig. 4 is a front elevational view thereof.

The box is shaded to represent contrasting colored areas.

I claim:

The ornamental design for a box for a watch, as shown and described.
